UNITED STATES PATENT OFFICE.

PHILIP E. G. ERICSON, OF ST. CHARLES, ILLINOIS, ASSIGNOR TO ST. CHARLES NET AND HAMMOCK COMPANY, OF ST. CHARLES, ILLINOIS, A CORPORATION OF ILLINOIS.

BASKET-BALL GOAL.

Application filed June 4, 1925. Serial No. 34,974.

To all whom it may concern:

Be it known that I, PHILIP E. G. ERICSON, a citizen of the United States, residing at St. Charles, in the county of Kane and State 5 of Illinois, have invented certain new and useful Improvements in Basket-Ball Goals; and I do declare the following to be a full, clear, and exact description of the invention, such as will enable others skilled in the art 10 to which it appertains to make and use the same.

My invention aims to provide an exceptionally simple and inexpensive, yet a very desirable goal for basket ball, the construction being such that the device may be folded into flat form, so that it will occupy very little space, permitting a number of the devices to be compactly stored in a stock-room or the like, and also permitting easy packing 15 for shipment, the construction being particularly advantageous for parcel post shipment.

With the foregoing in view, the invention resides in the novel subject matter hereinaf- 20 ter described and claimed, the description being supplemented by the accompanying drawing.

Figure 1 is a side elevation.

Figure 2 is a top plan view.

Figure 3 is a side elevation showing the device folded into flat form.

In the drawing above briefly described, the numeral 1 designates a horizontal ring formed by curving a single metal strip, the 35 ends of this strip being extended horizontally outward from the ring, in diverging relation, to provide a pair of supporting arms 2 whose outer extremities are laterally bent to form attaching ears 3. At their inner ends, the arms 2 are provided with parallel portions 4, and one end of a twisted metal brace 5 is received between these portions. A single bolt, rivet or other fastener

6 passes through the portions 4 and through the brace 5, so that said portions and the 45 ring 1 are held against spreading, and the brace 5 is pivoted to the arms. The outer end of this brace is bent to provide an attaching ear 7.

The ears 3 and 7 may be secured to an appropriate support 8, by screws or the like 9, and the ring 1 will then be rigidly supported in operative position, said ring of course being provided with the usual net 10.

When a number of the devices are to be 55 stored compactly before they are mounted for use, or when packing for shipment, the braces 5 may be swung into the rings 1, as shown in Fig. 3, so that a flat, compact form is imparted to each device, with obvious ad- 60 vantages.

Excellent results have been obtained from the details disclosed, and they are therefore 65 preferably followed. However, within the scope of the invention as claimed, slight modifications may, of course, be made.

I claim:

A basket ball goal comprising a single strip of metal curved to form a ring, said strip having its ends directed outwardly in 70 diverging relation from said ring to form a pair of supporting arms whose outer ends are laterally bent to provide attaching ears, said arms having parallel portions adjacent the ring, a brace having an attaching ear at 75 one end and having its other end disposed between said parallel portions of said arms, and a single fastener passing through said parallel portions of said brace to secure the arms and ring against spreading and to 80 pivot said brace to said arms, permitting folding of the brace into the ring when the device is to be packed or stored.

In testimony whereof I have hereunto affixed my signature.

PHILIP E. G. ERICSON.
